CRIMPING DEVICE

Roland Roswell Nydegger, Wilmington, Del., assignor to E. I. du Pont de Nemours & Company, Wilmington, Del., a corporation of Delaware

Application December 24, 1937, Serial No. 181,646

4 Claims. (Cl. 86—22)

The present invention relates to a new and improved crimping device, and, in particular, to a device suitable for crimping blasting cap shells.

The art of crimping shells had its origin in the manual operation performed with modified pliers, or the like, in securing fuse in ordinary blasting initiators. Such means failed to produce a uniform bead around the shell and the crimp formed did not effect a waterproof joint between said fuse and shell.

With the devising of a satisfactory resilient plug for electric blasting initiators, as disclosed and claimed in the co-pending case Serial No. 181,645, filed Dec. 24, 1937, it becomes even more necessary to have a crimping device free from the foregoing disadvantages.

The object of the present invention is the production of a new and improved device for crimping shells. A further object is such a device capable of producing a waterproof joint. An additional object is a simple mechanized crimping device capable of forming a uniform bead about the shell. Other objects will be apparent from the following detailed description of my invention.

I have discovered that the foregoing objects are attained by means of a crimping device which comprises a blade provided with a crimping slot. The slot is constructed with a substantially central enlargement, preferably circular in form, to permit free insertion or withdrawal of the shell. The remainder of the slot, on each side of the central enlargement, has a width smaller than the outer diameter of the shell, to cause the formation of a uniform concave or internal bead on the shell, when the crimping blade is reciprocated. The end portions of the slot are substantially semi-circular in form and play an important role in effecting an absolutely uniform bead around the shell. The side and end portions of the slot are bounded by a crimping edge of predetermined width and sharpness dependent on the depth and slope of crimp.

The crimping blade may be reciprocated by hand or any suitable actuating means. I prefer to employ cranking means for this purpose.

The shell is preferably held rigid during the reciprocation of the blade. Although any suitable anchoring device may be employed for this purpose, I prefer to use blocks which, when drawn together, form a groove for retention of the shell. Desirably these blocks are so actuated by cam action, or the like, that they separate and release the shell after it has returned to a central position with respect to the crimping blade. The camming lever may be actuated by the same crank which actuates the crimping blade.

The invention may be more readily understood by reference to the drawings which represent

merely a preferred embodiment and are not intended to act as a limitation upon the scope of the invention.

Referring generally to the drawings, the same numerals are employed to designate similar parts throughout the various views. Figure 1 is a plan view of the crimping blade, with cross-section 1—1 showing the crimping edge thereof. Figure 2 is a side view of one of the anchoring blocks, while Figure 3 is a side view of the crimping blade resting in one anchoring block. Figure 4 is a view of the blade between both blocks. Figure 5 is a view of a crimped shell. Figure 6 represents mechanical means for actuating the device and reciprocating the crimping blade. Figure 7 is a view of a plurality of crimping blades between both blocks. Figure 8 is a view of a shell provided with a plurality of crimps.

Referring in greater detail to the drawings, the crimping blade 1, of Figure 1 is provided with the slot 2 of preferred shape, as indicated by the substantially central enlargement 3 for introduction of the shell, narrow side portions 4 and 5, and semi-circular end portions 6 and 7. The section 1a—1a of the blade illustrates the crimping edge 8, which desirably bounds the side and end portions of the slot. In assembling the crimping device, the crimping blade 1 is placed in the groove 9 of Figure 2, between the anchoring blocks 10 and 11, as shown in Figures 3 and 4, and the enlargement 3 is aligned with the aperture 12, formed by joining the blocks 10 and 11, so that the shell can be inserted readily. In the crimping operation, the crimping blade is reciprocated in the groove 9 with respect to the aperture 12, and a shell contained therein. During the reciprocating stroke, effected by the action of the crank in Figure 6, the central enlargement of the slot is shifted, and one end portion comes in contact with the walls of the shell. This action imparts a uniform concave or internal bead half way around the circumference of said shell. As the stroke continues, the other end portion is brought into similar contact with the shell, thus effecting a bead around the remaining portion of the circumference, completing the crimp. The central enlargement of the slot then returns to its starting position to permit the removal of the crimped shell, the blocks being separated at this time. The completed crimp 13 is shown in Figure 5.

Figure 6 shows one method of actuating the crimping blade 1 and for maintaining the blocks in place during the crimping operation. Figure 6 is a plan view of the crimping blocks and crank shaft 18 which is held to base plate 22 by bearings 21. 14 illustrates a crank shaft head which may be driven by means of a belt attachment or other well-known drive mechanism. The crimping blade 1 is connected to said crank shaft by

means of the connecting rod 16, being fastened thereto at 17, while the other end of the connecting rod surrounds the crank pin at 15. The distance which the crimping blade reciprocates is, of course, determined by the design of said crank pin, which design is in turn governed by the length of crimping slot in the crimping blade.

The crimping blocks 10 and 11 are also held to base plate 22, block 10 being held securely with screws 20 while block 11 is held slideably by cleats 19. Spring 23 acts continuously on block 11 to open aperture 12. Opposing the action of spring 23 is contact screw 28 which is actuated by lever 24 to pivot at 29 by the action of cam 25 mounted on crank shaft 18. Cam 25 has one groove into which roller 27 may descend so that blocks 10 and 11 may separate under the action of spring 23 during the loading operation. The mechanism, as shown, is holding a shell and crimping the side away from the crank shaft 18 which is rotating in a clock-wise direction. This represents the first quarter of the crimping cycle.

In the foregoing detailed description, the principle of the device according to my invention has been described with reference to a single crimping blade. In actual operation I prefer to employ a plurality of said crimping blades. This preferred embodiment is illustrated in Figure 7 which shows two such crimping blades, 1 and 1-b placed in grooves one over the other between the anchoring blocks 10 and 11. The enlargement 3 in the slot of each of these blades is aligned with the aperture 12 formed by joining the blocks 10 and 11, so that the shell can be inserted readily. In the crimping operation, we prefer to reciprocate both blades at the same time about a shell contained in aperture 12, said reciprocating action being carried out as described in the foregoing in connection with the single blade. As a result of operating with two blades, the completed crimp will take the form shown as 13 and 13-a of Figure 8. Naturally, I do not intend to be limited to two blades, but may employ any number of said crimping blades.

Several outstanding advantages are attained with the use of my crimping device. When this device is employed to crimp a shell about the resilient plug disclosed and claimed in my co-pending application, Serial No. 181,645, filed Dec. 24, 1937, for example, an absolutely waterproof closure is attained.

In addition, the bead thus formed is absolutely uniform, and the crimping mechanism is extremely simple, having a relatively small number of moving parts. The latter factor lends greater safety in operation, wherever explosives are involved. The simple reciprocating stroke of my device is a distinct advance over the devices of the art wherein either the shell or the crimping means must be reversed or the use of moving jaws be employed to complete the crimp.

In the foregoing description, the crimping device has been designed in general for producing a single crimp in the cap shell. It should be understood, however, that two or more crimps may be produced in the same shell, either simultaneously or successively, by the employment of more than one crimping blade, one above the other, positioned in more than one horizontal slot preferably.

Although the device of my invention is especially designed to form the waterproof closure about the resilient plug, as disclosed and claimed

in co-pending case Serial No. 181,645, filed Dec. 24, 1937, the crimping device is not limited to such use but is of advantage in any situation where a uniform bead about a cylindrical shell is desired, and especially for crimping fuses in place in ordinary blasting initiators.

As many widely different embodiments may be employed without departing from the spirit and scope of my invention, I intend to be limited only by the following claims.

I claim:

1. A device for crimping shells, comprising a blade provided with a crimping slot of predetermined width bounded by crimping edges substantially parallel but converging at each end of said slot to form substantially semicircular end portions, said crimping slot being provided with a substantially central enlargement adapted to receive a shell substantially at right angles to the plane of said blade, anchoring means for retaining said shell in a fixed position, and means for reciprocating said blade to form a uniform bead around said shell.

2. A device for crimping shells, comprising a blade provided with a crimping slot of predetermined width bounded by crimping edges substantially parallel but converging at each end of said slot to form substantially semicircular end portions, said crimping slot being provided with a substantially central enlargement adapted to receive a shell substantially at right angles to the plane of said blade, anchoring means for retaining said shell in fixed position including a grooved block, said crimping blade being disposed substantially at right angles to the longitudinal axis of said groove, and means for reciprocating said blade to form a uniform bead around said shell.

3. A device for crimping shells, comprising a blade provided with a crimping slot of predetermined width bounded by crimping edges substantially parallel but converging at each end of said slot to form substantially semicircular end portions, said crimping slot being provided with a substantially central enlargement adapted to receive a shell substantially at right angles to the plane of said blade, anchoring means including a block having one groove adapted to retain said shell in fixed position and a second groove substantially at right angles to and intersecting said first groove, said crimping blade being movably disposed in said second groove so that the central enlargement in the crimping slot is adapted to center with said first groove to receive said shell, and means for reciprocating said blade in said second groove to form a uniform crimp around said shell.

4. A device for crimping shells, comprising a plurality of crimping blades each provided with a crimping slot of predetermined width bounded by crimping edges substantially parallel but converging at each end of said slot to form substantially semicircular end portions, said crimping slot being provided with a substantially central enlargement adapted to receive a shell substantially at right angles to the plane of said blade, anchoring means for retaining said shell in fixed position including a grooved block, said crimping blades being disposed substantially at right angles to the longitudinal axis of said groove, and means for reciprocating said blades to form uniform beads around said shell.

ROLAND R. NYDEGGER.
